UNITED STATES PATENT OFFICE.

HARRY W. HARDINGE, OF NEW YORK, N. Y.

APPARATUS FOR CRUSHING ORES AND OTHER MATERIAL.

1,367,777.

Specification of Letters Patent.

Patented Feb. 8, 1921.

Application filed February 6, 1919. Serial No. 275,299.

To all whom it may concern:

Be it known that I, HARRY W. HARDINGE, a citizen of the United States, residing at New York, county and State of New York, have invented certain new and useful Improvements in Apparatus for Crushing Ores and other Material, of which the following is a full, clear, and exact description.

The invention which constitutes the subject matter of this application relates to an apparatus for disintegrating ores or other materials. From a more specific aspect the invention relates to improvements in conical mills whereby the time and power required to reduce a predetermined quantity of comparatively soft material to a predetermined size are minimized. The nature of the invention will be more readily understood by first describing a specific form of apparatus by which the same may be carried out in practice.

In the drawings:

Figure 1 illustrates a longitudinal section of a conical mill showing my invention. Fig. 2 illustrates a skeletonized form of shell that may be employed in lieu of the perforated shell illustrated in Fig. 1.

Fig. 3 illustrates a modified form of lining that may be used in connection with the shells illustrated in Figs. 1 and 2.

Referring to the drawings in detail the reference numeral 10 designates what is commonly referred to as the inlet portion, 11 the cylindrical portion and, 12 the outlet portion of the mill. The entire walls of the mill, and in particular the cylindrical and outlet portions thereof, are provided with perforations 13 to enable the crushed material to pass directly to the outlet. Surrounding the mill is a non-rotating housing 14, in which the mill revolves serving to convey the crushed material to any suitable discharge point such as indicated by the reference numeral 15. The numeral 16 designates a gear wheel which is suitably connected to some power operating device whereby the mill may be rotated upon its longitudinal axis, while the numeral 17 designates the grinding media employed within the mill for grinding or crushing the material fed thereto.

The interior walls of the mill are provided with a replaceable lining 18 provided with perforations therein corresponding to the perforations 13 in the shell of the mill.

In Fig. 2 is illustrated a shell of skele-

tonized construction. It has this advantage that owing to the large openings 13' therein the perforated lining material may be placed therein without regard to the position of its openings, as is the case in Fig. 1 where the perforations in said lining must be made to register with the perforations in the shell. In other words, each hole in the shell which is illustrated in Fig. 2 is adapted to register with a plurality of perforations in the liner.

The chief advantage of the so-called conical mill over the cylindrical type is found in the saving of operating power and in the lessened wear and tear on the mill structure. For example, a conical mill usually requires for driving it at least fifty per cent. less power than a cylindrical mill of the same output. The remarkable efficiency of the conical type of mill is due to the fact, fully explained in my prior Patent No. 908,861, that the grinding bodies and the masses and lumps of material undergoing disintegration in the mill arrange themselves in a sort of vertical stratification according to size, the bodies and masses being largest in the zone of greatest diameter and gradually diminishing in size toward the apex of the conical outlet portion. The result is that the larger masses are subjected to heavy forces or impacts and the smaller masses to correspondingly lighter impacts. When the mill is operated at its rated capacity the assorting of the material to size is remarkably accurate, but if the material is fed to the mill too fast, as is often done in the effort to increase its output, the fines do not travel toward the outlet as fast as they should, with the result that the coarse particles find themselves embedded in fine material. The latter has a pronounced cushioning effect, which prevents the impacts of the masses, as they are tumbled about, from being fully exerted on the partly crushed pieces, especially in the zones of smaller diameter, where the bodies and masses are smaller and therefore lighter, and have less fall. The net result is that large proportion of coarse particles pass out with the fines. As smaller pieces are broken from the larger pieces the smaller disintegrated particles find their way through the spaces between the grinding media and out of the orifices in the shell and lining, thus tending to eliminate the cushioning effect which greatly militates against further disintegration of the remaining larger pieces.

As the larger pieces diminish

in size, but not sufficiently small to pass the orifices nor requiring the initial force for further division, they migrate to zones of the cone of smaller diameter, when they are 5 acted upon by the diminishing size of grinding media and energy forces, maintaining a fair relation between actual necessary breaking force and resistance to division and are discharged as soon as disintegrated 10 to a size sufficiently small to pass through the perforations in the cone.

The perforations or apertures are particularly advantageous in the conical outlet portion of the mill, as it is here that the cushioning effect spoken of is most serious, and it is also important to have the interior of 15 the conical outlet portion of the mill free, that is, devoid of barriers, dams, or other obstacles, so that the masses and pieces can 20 assort themselves freely.

I claim:

1. In a conical mill, a drum having a coni-

cal outlet portion free from inner obstructions and containing a multiplicity of freely and individually tumbling, crushing elements, the major portion of the lateral surface of said conical portion having outlet openings to permit escape of the material as fast as it is reduced to particles of a predetermined size. 25

2. In a conical mill, a barrel or drum having a conical outlet portion and containing a multiplicity of freely and individually rolling, crushing elements, the interior of the conical outlet portion being free from 35 obstructions to the free assorting of the material according to size and having a multiplicity of apertures in its wall to permit escape of the material as fast as it is reduced to particles of predetermined size. 40

In testimony whereof I hereunto affix my signature.

HARRY W. HARDINGE.
